UNITED STATES PATENT OFFICE

WILLIAM KONWISER, OF BROOKLYN, NEW YORK

DESIGN FOR A FASTENING MEANS OR SIMILAR ARTICLE

Application filed October 12, 1929. Serial No. 33,022. Term of patent 3½ years.

To all whom it may concern:

Be it known that I, WILLIAM KONWISER, a citizen of the United States, residing at Brooklyn, New York, in the county of Kings and State of New York, have invented a new, original, and ornamental Design for Fastening Means or similar article, of which the following is a specification, reference being had to the accompanying drawing, forming part thereof.

The figure is a perspective view of fastening means, showing my new design.

I claim:

The ornamental design for a fastening means, or similar article, as shown.

WILLIAM KONWISER.
